UNITED STATES PATENT OFFICE

PETER M. CIRIMELE, OF LOS BANOS, CALIFORNIA

INDICATOR FOR WRECKED SUBMERGED CRAFTS

Application filed October 26, 1927. Serial No. 228,945.

My invention relates to improvements in indicators for wrecked submerged crafts, and it consists in the combinations, constructions, and arrangements hereinafter described and claimed.

An object of my invention is to provide an indicator for wrecked submerged crafts, such as aeroplanes, submarines, boats, etc., in which a novel pressure actuated release 10 is used for freeing a buoy when the craft sinks to a predetermined depth.

A further object of my invention is to provide a device of the type described, which is extremely simple in construction and which 15 may be manually released or automatically released.

Other objects and advantages will appear in the following specification, and the novel features of my invention will be particularly 20 pointed out in the appended claims.

My invention is illustrated in the accompanying drawing forming a part of this application, in which:

Figure 1 is an end elevation of the device;

Figure 2 is a side elevation of the device; and

Figure 3 is an enlarged sectional view through the device.

30 In carrying out my invention I make use of a supporting surface 1 that may be a part of an airship, submarine, boat, or the like, and to this supporting member I secure a frame consisting of two uprights 2 and 3. These uprights are spaced a substantial distance apart to rotatably carry there-

35 between a spool 4.

Figure 3 shows how the spool is rotatably mounted on trunnions 5 and how the disc-shaped ends 6 of the spool are received in housings 7 formed integral with the uprights 2 and 3.

40 A friction brake 8 bears against one of the discs 6 and is yieldingly held in this position by a spring 9. This construction prevents the spool 4 from rotating too rapidly, and thus stops any tangling of the cable 10 as it is fed off from the reel. The friction brake 8 may be moved into operative position 45 by a handle 10'.

The cable 10 is connected to a spherical-shaped buoy 11 at one end, and to the reel 4 at its other end. The cable may be of any length desired and is preferably a fine, strong wire of copper, brass, or steel, between one 55 and two miles in length, or longer. It is well known that a sinking vessel will continue to drop until it strikes the floor of the ocean and in some instances this may be three to five miles beneath the surface. 60 The cable or wire 10 should be of sufficient length to permit the buoy to float on the surface regardless of the distance the craft sinks.

The means for housing the buoy consists of two cup-shaped members 12 and 13. The member 13 is formed as a part of the upright 3, while the member 12 is movable toward or away from the member 13. The member 12 is mounted upon a lever 14 that has a pivotal connection 15 to a projection 16 extending from the upright 2. The lower end of the lever 14 is pivotally connected at 17 to a piston arm 18 that in turn has a pivotal connection at 19 with a piston 20.

The piston is slidably received in a cylinder 21, and is urged in the direction of the arrow shown in Figure 3 by a spring 22. The spring 22 may be tensioned by means of an adjusting nut 23 for a purpose herein-after described. A spring check valve 24 75 permits the air contained within the cylinder to pass therefrom, but prevents the entrance of air through the valve.

From the foregoing description of the various parts of the device, the operation 85 thereof may be readily understood.

As stated at the start of the specification, the buoy 11 is automatically released when the craft to which it is attached sinks to a predetermined point. This is caused by the pressure of the water upon the piston 20, driving the piston against the tension of the spring 22 until the piston has moved a distance sufficient to swing the cup-shaped member 12 into the dotted line position shown in Figure 2. It is obvious that a tensioning of the spring 22 by the adjusting nut 23 will require a greater pressure of water upon the piston 20 before the buoy 11 is released. In 90 this way the device can be designed for re- 95

leasing the buoy at different levels below the surface of the water and searching parties will know approximately the depth at which the craft has sunk, and can act accordingly.

5 In addition to the automatic release I provide a manually actuated release shown in enlarged detail in Figure 3. This construction comprises a manually operated plunger 25 that works against a bell crank lever 26, which in turn is operatively connected to a piston rod 18 by means of a pin 27. The operation of this part of the device is apparent.

Although I have shown and described one embodiment of my invention, it is to be understood that the same is susceptible of various changes and I reserve the right to employ such changes as may come within the scope of the appended claims.

20 I claim:

1. An indicator for wrecked submerged crafts comprising a frame, a reel carried thereby, a buoy, a cable connected to said buoy and wrapped around said reel, said frame having a cup-shaped member for bearing against the side of said buoy, and a second cup-shaped member normally held against the other side of said buoy for securing the buoy to the frame, a lever carrying said second named member and being pivotally secured to said frame, a piston rod for moving said lever, and a piston acted upon by the pressure of the water for releasing said buoy at predetermined depths.

35 2. An indicator for wrecked submerged crafts comprising a frame, a reel carried thereby, a buoy, a cable connected to said buoy and wrapped around said reel, said frame having a cup-shaped member for bearing against the side of said buoy, and a second cup-shaped member normally held against the other side of said buoy for securing the buoy to the frame, a lever carrying said second named member and being pivotally secured to said frame, a piston rod for moving said lever, a piston acted upon by the pressure of the water for releasing said buoy at predetermined depths, and manually-controlled means for actuating said piston rod for releasing said buoy at any depth.

PETER M. CIRIMELE.
